UNITED STATES PATENT OFFICE.

SOPHUS CHRISTOPHER HAUBERG, OF COPENHAGEN, DENMARK.

LIQUID-SEPARATOR.

SPECIFICATION forming part of Letters Patent No. 705,669, dated July 29, 1902.

Application filed January 15, 1901. Serial No. 43,361. (No model.)

To all whom it may concern:

Be it known that I, SOPHUS CHRISTOPHER HAUBERG, director, of 32 Tagensvej, Copenhagen, in the Kingdom of Denmark, have invented certain new and useful Improvements Relating to Liquid-Separators, of which the following is a specification.

The present invention relates to liquid-separators; and the object is an arrangement for keeping in position the inner structure thereof. The result aimed at is to fix the said structure in such a manner that in spite of the quick rotation it cannot possibly be displaced. Even a very slight displacement of the inner structure during the rotation would make the drum side-heavy, which might bring about a breakage of the driving-spindle and expose the attendants to the greatest danger. In balance centrifugal separators—
i. e., separators in which the drum is placed loosely on the top of the driving-spindle—an absolutely firm fixing of the inner structure is of vital importance. This kind of separators, which, after all, are the only separators free from danger, may only be used in connection with inner structures if the said inner structure is firmly fixed.

In the accompanying drawings, forming part of this specification, Figure 1 is a view in vertical section, illustrating my improvements; and Fig. 2 is a horizontal section on a plane through line A B of Fig. 1.

In both figures like letters of reference wherever they occur indicate corresponding parts.
a and b represent, respectively, the upper and lower parts of the separator-drum, which are screwed together. Between the rims of the two parts there is arranged on the inner side of the drum a groove into which a plane edge l of the conical plate d, that carries the partitions c, may be placed and held when the two parts a and b are screwed tightly together. The partitions c have the same conical shape as the plate d and are placed below this one. Below the bottom one of the partitions is arranged a thicker conical plate f, of the same shape as the partitions c and provided with a cylindrical feed-pipe g, passing up through apertures in the partitions and through a cylindrical hole in the upper part of the plate d, projecting above the upper edge of this plate. The upper part of the pipe g is screw-

threaded and supplied with a nut h, that may be screwed home against the upper edge of the neck i of the plate d. When the nut h is 55 screwed down against the neck i, the pipe g and the plate f will be drawn up toward the partitions, and these will consequently be pressed tightly against one another and against the fixed plate d. The partitions are 60 in well-known manner supplied with lugs or the like for preventing the conical surfaces of the partitions from lying too closely to one another. These lugs are not shown on the drawings. 65

When the inner structure of the separator is fastened to the plate d in the above-described manner, the edge l of this plate may be inserted between the two parts a and b of the drum and kept in a firm position when 70 the said parts are screwed tightly together.

The separator is, for the rest, arranged in the usual manner. The plate f is guided by a gudgeon k, fixed to the bottom of the drum b and projecting into a cavity in the plate f. 75 The upper part a of the drum is at the top terminated in a cylindrical neck m, which is provided at top and bottom with two annular plates n and o. Through a tube p, placed inside the part a and attached to the plate o, 80 the milk is led from the separator to the space between the plates n and o and thence through the pipe q to the exterior. Diametrically opposite the tube p and between the plates n and o is placed a half-cylindrical tube r, 85 through which the cream that has come into the space t through the openings s in the conical plate d is led up above the plate n to the exterior. 90

Having now particularly described and ascertained the nature of this said invention and in what manner the same is to be performed, I declare that what I claim is—

1. In a separator of the character herein set forth, in combination, a two-part outer drum, 95 an inner conical plate, and conical partitions attached to said plate, the lower margin of the said plate being clamped between the upper and lower parts of the drum, substantially as and for the purposes explained. 100

2. In a separator of the character herein set forth, in combination, a two-part outer drum, an inner conical plate of which the lower margin is clamped between the two parts of

the drum, conical partitions, a second conical plate within the drum, a central feed-pipe, a nut upon the top of the latter, and a gudgeon fixed to the bottom of the drum and projecting into a cavity in the second conical plate, the parts being arranged substantially as and for the purposes explained.

In testimony that I claim the foregoing as my invention I have signed my name in presence of two subscribing witnesses.

SOPHUS CHRISTOPHER HAUBERG.
